UNITED STATES PATENT OFFICE.

HENRY B. ETTER, OF HORATIO, OHIO.

SPRING-COUPING.

SPECIFICATION forming part of Letters Patent No. 226,446, dated April 13, 1880.

Application filed January 21, 1880.

To all whom it may concern:

Be it known that I, HENRY B. ETTER, of Horatio, in the county of Darke and State of Ohio, have invented certain new and useful 5 Improvements in Spring-Couplings; and I do hereby declare the following to be a full, clear, and exact description of the same.

My invention relates to an improvement in spring-couplings designed especially for connecting single-trees to the double-tree of a vehicle, or for general use wherever a spring-coupling is required.

The novelty consists in the construction of the device and in the arrangement of its parts, 15 combining strength with simplicity and efficiency, as will be herewith set forth and specifically claimed.

In the accompanying drawings, Figure 1 represents a side elevation of my improved 20 coupling. Figs. 2 and 3 represent the draw-bars detached. Fig. 4 is a plan view, showing the application of my improved coupling to a vehicle.

The device consists of two metal draw-bars, 25 A and B, Figs. 2 and 3, of which the former, A, has a longitudinal slot through it, so as to form two arms or prongs, *a*. The upper or jointed end is formed into a hook, as represented. The other draw-bar, B, is a straight 30 piece of metal, square in section, having one end formed into a hook, *c*, and having upon the other end a right-angular cross-piece, D, with its ends turned up, as shown. The bar B lies between the prongs *a* in the slot formed in 35 the piece A, as seen in Fig. 1. Coiled around both of these bars is a spiral steel spring, E, one end of which rests upon the cross-piece D, and is embraced by the turned-up ends *c*.

To hold the parts thus together a flat metal piece, F, having a central square slot for the 40 passage of the bar B, is riveted or otherwise secured upon the ends of the prongs *a*, as seen in Fig. 1.

If desired, the plate F may have its ends turned up in similar manner to the cross-piece 45 D, so as to embrace the opposite ends of the spring.

It will be found by this construction that this device is self-supporting, strong, and compact, the turned-up ends *c* of the plate D 50 preventing the spring from spreading or slipping off.

When the coupling is attached to a single-tree and a double-tree, as shown in Fig. 4, it forms a yielding connection, and serves to 55 break and deaden the jars which would otherwise be felt if a rigid connection were used.

I am aware that spring-couplings have been before used containing springs and draw-bars; but

What I claim as new is—

The herein-described spring-couplings, consisting of the integral forked draw-bar A, with its end piece, F, containing a central square slot, the draw-bar B, with its cross-piece D, 65 having turned-up ends *c* to embrace the spring, and the circumcoiled spring E, the parts being constructed and relatively arranged in the manner and for the purpose specified.

Witness my hand this 11th day of August, 70
A. D. 1879.

HENRY B. ETTER.
